Primary Examiner — Philip S Hyder*Assistant Examiner* — Darlington Ly(57) **CLAIM**

The ornamental design for a zippered vehicle rear bumper protector, as shown and described.

DESCRIPTION

FIG. 1 is a top plan view of a zippered vehicle rear bumper protector showing my new design;

FIG. 2 is a bottom plan view thereof;

FIG. 3 is a right side elevation view thereof, the opposite side being a mirror image of the shown;

FIG. 4 is a front elevation view thereof;

FIG. 5 is a rear elevation view thereof;

FIG. 6 is an isometric view thereof; and,

FIG. 7 is an in-use isometric view thereof.

The broken lines in FIG. 7 of the drawings depict a vehicle trunk as environmental subject matter only and form no part of the claimed design.
